No. 830,068.

PATENTED SEPT. 4, 1906.

W. A. HEARTT.
GRAVITY LOCK FOR WINDOWS.
APPLICATION FILED JUNE 9, 1905.

UNITED STATES PATENT OFFICE.

WILLIAM A. HEARTT, OF NEW YORK, N. Y., ASSIGNOR TO FRANK VOIGTMANN, OF CHICAGO, ILLINOIS, AND SILAS H. POMEROY, OF NEW YORK, N. Y., COMPOSING THE FIRM OF VOIGTMANN AND COMPANY, OF CHICAGO, ILLINOIS.

GRAVITY-LOCK FOR WINDOWS.

No. 830,068.

Specification of Letters Patent.

Patented Sept. 4, 1906.

Application filed June 9, 1905. Serial No. 264,401.

To all whom it may concern:

Be it known that I, WILLIAM A. HEARTT, a citizen of the United States of America, and a resident of New York, State of New York, 5 have invented a certain new and useful Improvement in Gravity-Locks for Windows, of which the following is a specification.

My invention contemplates an improvement on the form of window-lock shown and 10 described in application, Serial No. 261,172, filed by me in the United States Patent Office on the 19th day of May, 1905.

Generally stated, the object of my invention is the provision of an improved and 15 highly-efficient window-lock of the general character shown and described in my said prior application.

A special object is to provide certain details of construction and features of improvement tending to increase the general efficiency and serviceability of a window-lock of 20 this particular character.

To the foregoing and other useful ends my invention consists in matters hereinafter set 25 forth and claimed.

In the accompanying drawings, Figure 1 is an inside view of a window provided with a lock embodying the principles of my invention. Fig. 2 is an enlarged front elevation of 30 said lock. Fig. 3 is a vertical section on line 33 in Fig. 2.

My improved lock can be applied to different kinds of windows. As shown, the window comprises a frame A, an upper tilting or 35 swinging sash B, and a lower sash C. Said upper sash is provided with pivots b and is thus adapted to tilt about a horizontal axis. Preferably the upper end of the sash B swings inward and its lower end swings outward. My improved lock for locking the 40 tilting sash in its upright or normal position comprises a bracket-plate D, provided with vertical slots d, through which extend the screws d', which adjustably hold the plate in 45 place upon the head or upper portion of the window-frame A. A locking-dog E is pivotally mounted upon the said plate and so formed that it will hang obliquely when the window is open. The said locking-dog has 50 an axis e, about which it is adapted to swing upward and outward when it is pushed out

of the way by the upper portion of the sash B—that is, when the window is closed. Another bracket-plate F is secured to the upper portion of the sash B by means of screws f. 55 This plate F has an inclined or beveled contact-surface f' for the end of the locking-dog E. It is also provided with a pair of ears f² and with stops f³ and f⁴. A weighted releasing-lever G is pivotally mounted upon 60 said ears and has its inner weighted end portion g adapted to engage the under side of the releasing-dog. The said lever is adapted to swing about its axis g' and is also provided with an outer arm g². At its inner end the 65 said lever is provided with a lug g³, adapted to play between the two shoulders f³ and f⁴. An operating cord or chain H is attached to the said arm g². With this arrangement a pull on the said cord or chain will raise the 70 inner end of the releasing-lever G and will cause the same to engage and lift the locking-dog E out of locking engagement with the contact-surface f'. The pull on the cord or chain then being continued, the window-sash 75 B will be pulled into the desired position. By temporarily securing the cord or chain to a catch or other device c on the lower sash the upper sash can be retained in its open or inclined position. In this way it is the initial pull on the connection for drawing open 80 the window which serves automatically to release the locking-dog. When the window is closed, the dog drops readily into place, and while the window remains closed the 85 weight of the dog tends constantly to produce a wedging pressure in a direction to more firmly close the window. Thus the lock is capable of a self-tightening action until the contact-surface f' is entirely worn 90 away and until the plate D reaches the limit of its downward adjustment, and, as stated, it is the inner end of a weighted lever which is used for lifting the dog out of engagement 95 with the sash. In this way the pull is exerted on the outer end of the lever, and the movement of the weight is in the same direction as the opening movement of the sash. Furthermore, the cord or chain is conveniently and accessibly attached to the outer 100 end of the lever.

The plate F constitutes a stop which is

provided with the releasing-lever G and the bevel or contact surface *f* for the end of the pivoted locking-dog.

What I claim as my invention is—

- 5 In combination with a window frame and sash, a window-lock comprising a bracket on the frame, a locking-dog pivoted on said bracket, a stop carried by the sash and provided with a contact-surface, and a weighted 10 releasing-lever pivoted on said stop and provided with a weighted inner end portion adapted to swing upward and outward, and

thereby lift the said locking-dog out of locking engagement with said contact-surface, the said locking-dog being pivoted at the 15 outer edge of the window-frame and adapted to swing inwardly underneath the same and be supported by the said contact-surface on the stop.

Signed by me this 3d day of June, 1905. 20
WILLIAM A. HEARTT.
